[57] CLAIM

The ornamental design for a fingerboard for guitar, as shown and described.

DESCRIPTION

FIG. 1 is a perspective view of a fingerboard for guitar, showing my new design;

FIG. 2 is a front view thereof; the rear view being identical;

FIG. 3 is a left side view thereof;

FIG. 4 is a right side view thereof;

FIG. 5 is a top view thereof;

FIG. 6 is a bottom view thereof; and,

FIG. 7 is a top view of the fingerboard applied on the guitar neck. The broken line showing of a guitar peghead is shown for environmental purposes only and forms no part of the claimed design.
